(57) **CLAIM**

The ornamental design for holiday ornament hanger assembly, as shown and described.

DESCRIPTION

FIG. 1 is an isometric view of a holiday ornament hanger assembly showing my new design.

FIG. 2 is a front elevation view thereof.

FIG. 3 is a top plan view thereof.

FIG. 4 is a left side elevation view thereof.

FIG. 5 is a right side elevation view thereof.

FIG. 6 is a rear elevation view thereof.

FIG. 7 is a bottom plan view thereof; and,

FIG. 8 is an isometric view thereof showing the holiday ornamental hanger assembly in a fully extended configuration.

The broken lines shown in the drawings depict environment, and form no part of the claimed design.
